(57) **CLAIM**

We claim the ornamental design for a camera tripod, as shown and described.

DESCRIPTION

FIG. 1 is a front-left-upper isometric view of a camera tripod in a first configuration.

FIG. 2 is a lower-right-upper isometric view of the camera tripod in the first configuration.

FIG. 3 is a front view of the camera tripod in the first configuration.

FIG. 4 is a right-side view of the camera tripod in the first configuration.

FIG. 5 is a back view of the camera tripod in the first configuration.

FIG. 6 is a left-side view of the camera tripod in the first configuration.

FIG. 7 is a top view of the camera tripod in the first configuration.

FIG. 8 is a bottom view of the camera tripod in the first configuration.

FIG. 9 is a back view of the camera tripod in a second configuration.

FIG. 10 is a front-left-upper isometric view of the camera tripod in a third configuration.

FIG. 11 is a top view of the camera tripod in the third configuration; and,

FIG. 12 is a right-side view of the camera tripod in the third configuration.

(Continued)

The broken lines shown in the drawings illustrate portions of the camera tripod and form no part of the claimed design.

1 Claim, 8 Drawing Sheets

Related U.S. Application Data

a continuation of application No. 16/501,118, filed on May 13, 2019, now Pat. No. 10,982,806.
